UNITED STATES PATENT OFFICE.

WILLIAM OLDMAN, JR., OF BUFFALO, NEW YORK.

DEVICE FOR HOLDING RIVETS.

SPECIFICATION forming part of Letters Patent No. 367,314, dated July 26, 1887.

Application filed December 6, 1886. Serial No. 220,781. (No model.)

To all whom it may concern:

Be it known that I, WILLIAM OLDMAN, Jr., a citizen of the United States, residing in Buffalo, in the county of Erie and State of New York, have invented certain new and useful Improvements in Devices for Holding Rivets while Riveting, of which the following is a specification.

The object of my invention is to provide the means for holding rivets while riveting a steam-boiler, or for other purposes, and will be fully and clearly hereinafter described and claimed, reference being had to the accompanying drawings, in which—

Figure 1 is a vertical central section through the outer casing of the device, showing a side elevation of the riveting-bar, the rubber or elastic disk, the reducing-bar and the handle or lever for operating it, also a section through a portion of a boiler. Fig. 2 is a plan or top view of the device. Fig. 3 is a detached side elevation of one of the reducing-bars. Fig. 4 is a bottom view of a removable rubber disk. Fig. 5 is a vertical central section through the same and the bolt by which it is secured in place; and Fig. 6 is a top view of the rubber disk or short cylindrical block.

In said drawings a portion, 1, of a steam-boiler is shown, showing the device in place within a boiler and holding a rivet in position to be riveted.

2 is an outer cylindrical portion or casing. It is preferably made of wrought-iron tubing about two and one-half inches inside diameter; but may be larger or smaller, if desired, and is slotted to receive the lever 12.

The riveting-bar 3 is usually made of two or two and a quarter inch round iron, and is provided with a tapering or reduced portion, 4, at the top, of cast-steel, which is preferably hardened or tempered.

It is provided with a depression or recess, 5, on the top, (see Fig. 1,) enough being broken away to show this depression, which is made so as to conform to the shape of the head of the rivet *a*.

This riveting-bar is made easily removable. Below it is a rubber disk or short cylindrical block, 6, to act as a cushion. Below the rubber disk 6 is a reducing-block, 7, which rests on the end 15 of the lever 12. All these parts

are made enough smaller than the casing 2 as to be easily removable.

8 and 9 represent two plates rigidly secured to the side of the casing and perforated with holes 10 and 11.

12 represents a lever having a handle, 13. It is adapted to be readily secured in any of the holes 10 or 11 by means of the bolt 14. The object of these holes 10 and 11 is to provide the means for adjusting the lever 12 up or down to any point desired. The office of the rubber block 6 is to relieve the reducing-bar 7, the lever 12, and the hand while holding it from the concussion produced by the hammering of the rivet.

16 represents a small removable pin adapted to fit into the rivet-holes 17 in the lower part of the boiler for keeping the lower end of the device in position when using it. This pin is 70 easily removable by unscrewing it from the cap 18. When there are no holes in the bottom of the boiler, this pin may be removed and the rubber disk 19 put on in its place by means of the bolt 20. (See Figs 4 and 5.) The depression 21 allows the head of the bolt to pass in, so as to be out of the way, and it may be deep enough to allow the head of the bolt to pass in far enough to allow room for the disk to rest on the boiler while the head of the bolt 80 is in the depression.

The operation of the invention is very simple, a rivet, *a*, being put in place, as shown, and then pressure enough is put upon the handle 13 to force the riveting-bar 3 up firmly 83 against it, in which position it is held securely, as shown in Fig. 1, until riveted.

There may be several of the bars 3 and 7, of different lengths, so that the device may be easily and readily adjusted and be used in 90 large or small boilers of various sizes.

For very light riveting the reducing-bar or the cushion, or both, may sometimes be dispensed with and the riveting-bar made long enough to adapt it to the use required; but for 95 general purposes it is best to have both.

I claim as my invention—

1. A device for holding rivets while riveting, consisting of an outer case or tube, a vertically-adjustable lever and handle, a riveting-bar having a depression to receive the head of the rivet, a rubber disk or cushion, and a re-

- ducing-bar, all being easily removable from the outer case and combined for joint operation, substantially as and for the purposes described.
5. 2. In a device for holding rivets, the combination of the outer case or tube, a vertically-adjustable lever, a removable riveting-bar having a depression to receive the head of the rivet, and a reducing-bar, as and for the purposes described.
3. The combination of the case 2, the riveting-bar 3, having a depression, 5, and the vertically-adjustable handle 12 13, all being easily removable from the case 2, as and for the purposes described.

WM. OLDMAN, JR.
